UNITED STATES PATENT OFFICE

FRANCIS J. LAPOINTE, OF ANN ARBOR, MICHIGAN

VERTICAL FULL BROACHING MACHINE

Application filed January 4, 1929. Serial No. 330,345.

My invention has for its object to provide a means whereby a pull broach may be readily inserted in the work and connected to the draw bar or head of a broaching ma-

chine. The invention enables a rapid broaching of articles in that it provides a means whereby the broach may be readily disconnected from the head upon its return, the work inserted in place and the shank, or starting end, of the broach inserted in the head, that will automatically lock the broach to the head. The invention is particularly advantageous when used in vertical broaching machines by reason of the vertical position of the broach which enables easy handling of the broach.

To illustrate a practical application of the invention, I have selected a broaching machine having an embodiment of my invention, and shall describe it hereinafter. The parts of the broaching machine that particularly relate to the construction containing the invention, are shown in the accompanying drawings.

Fig. 1 is a side view of the head of a broaching machine. Fig 2 is an end view of the part illustrated in Fig. 1. Fig. 3 is a view of a section taken on the plane of the line 3—3 indicated in Fig. 1. Fig 4 is a view of a section taken on the plane of the line 4—4 indicated in Fig. 3. Fig. 5 is a view of a section similar to that shown in Fig. 4. It illustrates parts located in positions different from that shown in Fig. 4. Fig. 6 is a view of a section taken on the plane of the line 6—6 indicated in Fig. 3. Fig. 7 illustrates a top view of a part of the locking member.

In the particular form of construction illustrated in the drawings, the broach draw head 1 is connected to the draw plate 2 of a vertical pull broaching machine. The draw plate 2 may be located on vertically disposed guide bars 3 and operated by a hydraulic means to reciprocably move the draw plate 2 along the guide bars 3. A work plate 4 may be secured to the guide bars 3 by suitable locking rings 5. The draw head 1 may be secured to the draw plate by means of a suitable threaded stud 10 and a nut 11,

The draw head is provided with means for automatically engaging the pull broach upon mere insertion of the pull broach into the head.

The work is located below the work plate 4 and the broach is inserted through the work and through the work plate or bed 4 and pushed up into the head wherein it is engaged. Upon the completion of the vertical movement of the broach on the work, the work drops from the work plate, or is removed, and the draw head descends. The broach is disconnected from the head which permits the broach to drop from the head 4, whereupon the succeeding article is located in position and the shank of the broach is inserted through the work and into the head.

The head is provided with a block 12 that is integrally connected with the threaded stud 10. The block 12 is slotted as at 13 and a pair of side blocks 14, having projecting parts 15, are bolted to the sides of the block 12 so as to locate the protruding parts 15 within the slot 13 of the block 12. The protruding parts 15 are provided with surfaces 16 that are inclined to the axis of the stud 10 so as to slope away from the stud and towards its axis. A pair of dogs 17 are also located within the slot 13 and are provided with surfaces 18 that conform to the surfaces 16 of the side blocks 14. The dogs 17 are so formed as to have a sliding movement on the surfaces 16 and thus to approach or recede from each other according to the direction of movement of the dogs 17 relative to the side blocks 14.

In order to engage the shank end of the broach, the dogs are provided with suitable engaging surfaces and the broach is provided with corresponding engaging surfaces that coact therewith to be locked by the engaging surfaces of the dogs. Any suitable recesses and projections that are complementary in their relation may be formed on the dogs and the shank of the broach for establishing connection between the broach and the dogs. In the particular form of construction shown, the shank end of the broach is threaded as at 20, while the dogs 17 are also threaded as 100

at 21 and upon downward sliding movement of the dogs 17, along the inclined surfaces 16, the dogs 17 will securely engage the threaded end of the broach. In order that connection of the threaded end of the broach with the dogs may be assured, the arc of the thread on each of the dogs is about 90 degrees, the remainder of the thread being cut away in the formation of the dogs, leaving 5 the flanges 23 at the ends of the threaded 10 portions 21 of the dogs that form extended lateral surfaces of the dogs for guiding the dogs in their movements within the slot 13 of the block 12. Thus, in order to connect 15 the broach to the head, the broach is merely inserted through the lower end of the slot 13 and between the protruding parts 15. The dogs 17 are slid along the surfaces 16 until the teeth or thread of the dogs mesh 20 with the teeth or thread of the broach. Preferably, a plate 24 is bolted to the lower side of the block 12 and is provided with an opening 25 which forms a guide for the shank of the broach and also provides a 25 means that cooperates to hold the broach in position.

In order to release the dogs 17 from the broach, a release bar 30 is located in a slot 29 extending transversely through the block 30 12. The release bar is provided with an opening 31 through which the end of the broach may freely pass when it is inserted into the head or withdrawn therefrom. The bar is also provided with laterally extending 35 portions 32 that are adapted to engage the lower ends of the dogs 17. When, therefore, the release bar is raised, the dogs will be lifted and will be loosened from the broach. The dogs may be separated by reason of in- 40 clined surfaces formed by the engaging teeth or thread of the broach and the corresponding inclined surfaces formed on the dogs. In the particular form of construction shown, the lower ends of the dogs 17 are pro- 45 vided with the surfaces 33 that are inclined outwardly and downwardly to the longitudinal axis of the head. The release bar 30 is also provided with inclined surfaces 34 that correspond to the inclined surfaces 33 of 50 the dogs so that when the release bar 30 is raised, the dogs 17 will tend to separate by sliding laterally over the surfaces 34. Thus, the dogs and the broach may be provided with plane engaging interlocking surfaces 55 rather than inclined engaging surfaces and by reason of the inclined surfaces 33 and 34 the dogs will disengage the broach.

The release bar 30 may be raised by any suitable means. In the particular form of 60 construction shown, a lever 40 is pivotally supported by means of, and is keyed to one end of, a pin 41 that extends through one of the side blocks 14. An arm 42 is connected to the opposite end of the pin 41 and the lever 40 and the arm 42 are provided with

oblong openings 44 in which the ends of the release bar 30 are located whereby, notwithstanding the arcuate movements of the lever and the arm about the axis of the pin 41, the release bar will move rectilinearly in the slot 70 31. When, therefore, it is desired to release the broach from the head, the lever 40 is raised which raises the release bar 30 and the dogs 17 separate. This will drop the broach from the head. 75

If desired, an automatic means may be provided for releasing the broach from the head upon the completion of the downward movement of the head. This may be performed by means of a dog 50 that is pivotally supported at any desired point for free angular movement in one direction and for limited movements in the opposite direction, namely, in the return direction of the movement of the head when it is desired to release the broach. The dog 50 may be pivotally supported on the bracket 51 that is connected to the work plate 4. When, therefore, the draw head 1 is raised, the lever 40 will rotate and pass the dog 50. The dog 50 is so formed as to provide a stop 52 to limit its return movement so that when the draw head 1 returns the end of the lever 40 will engage the dog 50 and before the completion of the downward stroke of the draw head, the lever 45 will rotate sufficiently to operate the release bar 30 to release the broach from the draw head. 90

In order to maintain the dog 17 in cooperative relation within the block 12, the dogs 100 17 may be interconnected by means of a bar 55 located in a slot formed in a side of each of the dogs. The bar 55 is, preferably, connected to one of the dogs 17 and is slidably located in the slot formed in the other dog 105 17. This operates to maintain the dogs in substantially the same relation with respect to the inclined surfaces 16 and causes them to move together. 110

I claim:

1. In a draw head for vertically operated pull broaching machines, the draw head having a pair of inclined surfaces extending towards the axis of the draw head and downwardly, a pair of dogs slidably supported on the said surfaces and having inwardly extending engaging parts for engaging the broach, the inwardly extending engaging parts having surfaces inclined upwardly to and outwardly from the axis of the draw 110 head, a release bar extending beneath the lower ends of the dogs for engaging the dogs, and means for raising the release bar, the last named surfaces operating to separate the dogs and release the broach when the release 120 bar is operated.

2. In a draw head for vertically operated pull broaching machines, the draw head having a pair of inclined surfaces extending towards the axis of the draw head and down- 130

wardly, a pair of dogs slidably supported on the said surfaces and having inwardly extending engaging parts for engaging the broach, the lower ends of the dogs having surfaces that are inclined to the axis of the draw head and extending downwardly and outwardly, a release bar for engaging the said surfaces to separate the dogs and release the broach, and means for raising the release bar.

10 3. In a draw head for vertically operated pull broaching machines, the draw head having a pair of inclined surfaces extending towards the axis of the draw head and downwardly, a pair of dogs slidably supported on the said surfaces and having inwardly extending engaging parts for engaging the broach, the lower ends of the dogs having surfaces that are inclined to the axis of the 15 draw head and extending downwardly and outwardly, a release bar for engaging the said surfaces, the release bar having inclined surfaces that correspond to the inclined end surfaces of the dogs, and means for raising 20 the release bar.

25 4. In a draw head for vertically operated pull broaching machines, the draw head having a pair of inclined surfaces extending towards the axis of the draw head and downwardly, a pair of dogs slidably supported on the said surfaces and having inwardly extending engaging parts for engaging the broach, the lower ends of the dogs having surfaces that are inclined to the axis of the 30 draw head and extending downwardly and outwardly, a release bar for engaging the said surfaces, the release bar having inclined surfaces that correspond to the inclined end surfaces of the dogs, and a lever pivotally 35 supported on the draw head for raising the 40 release bar.

5. In a draw head for vertically operated pull broaching machines, the draw head having a pair of inclined surfaces extending towards the axis of the draw head and downwardly, a pair of dogs slidably supported on the said surfaces and having inwardly extending engaging parts for engaging the broach, the lower ends of the dogs having 45 surfaces that are inclined to the axis of the draw head and extending downwardly and outwardly, a release bar for engaging the said surfaces, the release bar having inclined surfaces that correspond to the inclined end 50 surfaces of the dogs, a lever pivotally supported on the draw head for raising the release bar, a pivoted latch member connected to a fixed part of the broaching machine and adapted to engage the lever at a point near 55 the completion of the stroke of the draw head to release the broach from the dogs.

60 In witness whereof I have hereunto signed my name to this specification.
